UNITED STATES PATENT OFFICE

106,280

DESIGN FOR A CHILD'S COSTUMER

Harry P. Brown, Baltimore, Md.

Application May 6, 1937, Serial No. 69,204

Term of patent 14 years

To all whom it may concern:

Be it known that I, Harry P. Brown, a citizen of the United States, residing at Baltimore and State of Maryland, have invented a new, original, and ornamental Design for a Child's Costumer, of which the following is a specification, reference being had to the accompanying drawing, forming part thereof.

The figure of the drawing is a perspective view of a child's costumer showing my new design.

I claim:—

The ornamental design for a child's costumer, as shown.

HARRY P. BROWN.
